(57) **CLAIM**

The ornamental design for a mop cloth, as shown and described.

DESCRIPTION

FIG. 1 is a top view of a mop cloth according to the invention;

FIG. 2 is a bottom view of the mop cloth according to the invention;

FIG. 3 is a left short side view of the mop cloth according to the invention;

FIG. 4 is a right short side view of the mop cloth according to the invention;

FIG. 5 is a left long side view of the mop cloth according to the invention;

FIG. 6 is a right long side view of the mop cloth according to the invention; and,

FIG. 7 is a perspective view of the mop cloth according to the invention.

1 Claim, 7 Drawing Sheets

FIG. 1

FIG. 2

FIG. 3

FIG. 4

FIG. 5

FIG. 6

FIG. 7
